UNITED STATES PATENT OFFICE.

JOHN E. BELL, OF BROOKLYN, NEW YORK, ASSIGNOR TO SINCLAIR REFINING COMPANY, OF CHICAGO, ILLINOIS, A CORPORATION OF MAINE.

FRACTIONATING TOWER FOR PRESSURE STILLS AND THE LIKE.

Application filed July 8, 1921. Serial No. 483,127.

To all whom it may concern:

Be it known that I, JOHN E. BELL, a citizen of the United States, residing at Brooklyn, in the county of Kings and State of New York, have invented certain new and useful Improvements in Fractionating Towers for Pressure Stills and the like, of which the following is a specification.

In the process of cracking gas oil and the like to make gasoline, the condensate from the pressure still contains in addition to the lighter hydrocarbons suitable as components of the gasoline, hydrocarbons of the kerosene group and others even heavier. It is therefore necessary to subject the condensate to redistillation to fractionate it into merchantable products and to separate out the heavier hydrocarbons. It is the purpose of the present invention to partially or entirely dispense with this redistillation by fractionally condensing the vapors as they come from the pressure still, separating the kerosene fraction and the heavier compounds from the gasoline vapors and separately condensing them. For this purpose I employ a fractionating condensing tower which has a series of vapor condensing chambers through which the vapors from the pressure still travel successively on their way to the final condenser for the gasoline fraction. The condensing surfaces in the successive chambers are maintained at successively lower temperatures so that the heaviest vapors are condensed in the first chamber entered by the vapors, the next heaviest vapors in the second chamber entered and so on. Tubes through which a cooling liquid such as high gravity oil flows, preferably constitute the condensing surfaces.

The nearer the temperature of the condensing surface approaches the critical temperature of the vapor to be condensed the more accurate is the fractionation, and theoretically it would be desirable that the surfaces be maintained at temperatures a few degrees only below the critical temperatures of the respective vapors to be condensed. Obviously, however, this would be impracticable because of the large number of compounds of different gravities in the vapors to be condensed and the great extent of condensing surface necessary for each where such a low temperature differential is maintained. It is necessary therefore

to sacrifice accuracy or definiteness in cut to some extent to practical considerations. In my improved fractionating tower, in the specific example thereof shown in the drawing and hereinafter described, the cooling oil or other cooling medium enters the condensing tubes of the last or coolest condensing chamber at a temperature within 25 degrees of that of the vapors leaving the chamber, the temperature of the condensing surface being somewhat intermediate the temperatures of the oil and vapors respectively. Furthermore the temperature of the oil leaving the tubes of the first condensing chamber is within 25 degrees of that of the vapors entering the chamber, and this temperature differential is substantially maintained throughout the condensing chambers of the tower. If desired the differential could be reduced to say 10 degrees but this would vastly increase the size of the apparatus, if the same cuts were to be made, for the reasons given above. If it were desired, for example, to condense all of the vapors in the tower including the gasoline fraction with a 25 degree temperature differential, supposing the vapors coming from the still to retain a temperature of say 530 degrees when they reach the tower, the oil for cooling the condensing tubes would enter at a temperature of say 65 degrees and leave at a temperature of about 505 degrees. By increasing the flow of cool oil or decreasing its initial temperature greater condensation could be achieved but at the expense of definiteness of cut. Preferably the gasoline fraction is not condensed in my fractionating tower but in a condenser to which it is led from the tower and which may be of usual or approved form. Thus, for example, with a tower of four condensing sections or chambers the first cut, condensed in the first or hottest section would contain neither gasoline nor kerosene and might be returned to the still or put in heavier stock. The next three cuts would be kerosene and could be marketed as such or the different cuts blended with each other or with stock from other sources in a variety of ways according to the specific composition desired. If no kerosene is desired the tower may be operated with a smaller drop in temperature of the cooling oil in the device. The kerosene and heavier fractions could be returned

from the first two chambers of the fractionating tower to the still and gasoline condensed in the other two chambers. Any cooling fluid, stable at the temperatures to which it would be subjected, might be employed but preferably I use a suitable oil which is constantly circulated through the tower, preferably in a direction opposite to that of the vapors, and through a cooler to absorb the heat from the oil and back to the tower by means of a suitable pump. In order to increase the efficiency of separation I may reflux all or any portion of the condensate from any or all of the condensing chambers, except the first or hottest, into the chamber of next higher temperature. For this purpose the tower is preferably vertical, as in the construction shown in the drawings, the series of vapor condensing chambers being superposed therein and the vapors entering at the bottom of the series and leaving from the top thereof. Condensate refluxed from an upper, cooler chamber to a lower, hotter chamber is mainly revaporized in the latter a small fraction only of heavier components, which have been carried over with the lighter vapors remaining behind in liquid form in the hotter chamber.

In the accompanying drawings I have shown a preferred embodiment of my invention and described the same in the following specification. It is to be understood, however, that the specific disclosure is for the purpose of exemplification only and that the scope of the invention is defined in the following claims in which I have endeavored to distinguish it from the prior art so far as known to me, without, however, relinquishing or abandoning any portion or feature thereof.

In the accompanying drawings Fig. 1 is a side elevation of an apparatus embodying a preferred form of my invention; Fig. 2 is an axial longitudinal sectional view of the same on an enlarged scale, partly broken away; Figs. 3 and 4 elevations partly in section of details, and Fig. 5 a horizontal section showing a detail.

Each part is identified by the same reference character wherever it occurs in the views.

In the preferred form of invention shown in the drawing the fractionating condensing tower comprises a cylindrical shell 4 closed by end plates 5-5, each of which is provided with a hand-hole fitting 6. The hand-holes are normally closed by plates 7-8. Slightly spaced from the end plates 5 at each end of the tower is a header sheet 9, 10, said sheets forming with the adjacent end plates inlet and outlet chambers 11, 12 for the cooling fluid as will presently appear. The space between the header sheets

ing chambers 13 shown as four in number, though, the number is optional and dependent upon the number of cuts desired. Between adjacent vapor condensing chambers are chambers 14 for the cooling fluid which chambers are formed by header sheets 15 on opposite sides thereof and the wall of the cylindrical tower, and the header sheets are connected by batteries of tubes 16 extending through the respective vapor condensing chambers, whereby the cooling fluid may flow the length of the tower through the cooling fluid chambers and said tubes. Preferably the vapor chambers are provided with suitable baffle plates 17 to provide a circuitous circulation for the vapors therethrough in order that they may be more thoroughly brought in contact with the cooling pipes.

The lowermost of the vapor chambers is provided with an inlet port 18 for the entrance of the vapors and the uppermost condensing chamber with an outlet 19. Provision is made for the flow of the vapors or such portion thereof as remains uncondensed from each vapor chamber (except the topmost) to that next above it by means of a by-pass tubular connection 20. As best shown in Figs. 2 and 3 this by-pass is formed of rectangular tubing, the end flanges 21 of which are secured in any suitable manner to the cylindrical wall of the tower above and below the intermediate cooling fluid chamber.

Preferably oil is the cooling fluid employed as heretofore stated and it is preferably circulated downwardly through the tower and is drawn off at the bottom, cooled and returned to the top of the tower. For this purpose a cooler 24 is connected by pipe 25 to cover plate 7 of the lower manhole 6, the other end of the cooler being connected by a pipe 26 to circulating pump 27 by which the oil is forced through pipe 28 to the top of the tower. It has not been considered necessary to illustrate in detail the cooler 24 as it may be of the usual tubular construction, the inlet for the water or other fluid for cooling the oil being shown at 29 and the outlet therefor at 30, Fig. 1. In order to properly control the gravities of the several cuts effected in the respective vapor condensing chambers, I have provided for controlling and distributing the flow of cooling fluid through the respective batteries of pipes in said chambers. For this purpose each of the intermediate cooling fluid chambers 14 is provided with an outlet 31, said outlets being connected to a common by-pass pipe 32 provided with hand valves 33 and connected by pipe 34 to the cooler. By means of this by-pass pipe more or less of the cooling fluid may be by-passed about any of the vapor condensing chambers except the first or it may be carried from any

of the cooling fluid chambers directly to the cooler. In order to keep the temperature conditions under close observation each of the vapor connections 20 is formed with a 5 thermometer well 35.

Each condensing chamber near its bottom has a drawoff pipe 23, which is provided at 36 with a gauge glass to indicate the level of the condensate in the chamber, and a 10 valve 37 for shutting off the draw-off and controlling the passage of condensate therethrough. A pipe 38 connected to the gauge glass extends to a cooler or storage tank. A branch connection 39 leads from the 15 draw-off 23 of each condensing chamber (except the lowermost) to the top of the next lower condensing chamber at 40, a trap being formed in said pipe at 41 and a valve located therein at 42. By means 20 of this connection the condensate from each condensing chamber may be refluxed to the next lower and hotter condensing chamber where it will be revaporized and returned for further treatment, the amount 25 of the reflux being controlled by valve 42.

The stream of condensate entering the top of the condensing chamber from pipe 39 spreads over the topmost baffle therein and, the holes in the baffle through which 30 the cooling tubes extend being somewhat larger than the latter, forms films on the tubes until vaporized being thus effectively subjected to the temperature of the tubes. By refluxing the condensate as described 35 it is in effect redistilled and refractionated thus securing a more definite cut.

From the foregoing it will be recognized 40 that my invention provides a compact and economical apparatus in which the vapors coming from the still can be divided into cuts as desired, the division between the several cuts being definite and under the operator's control, thus dispensing with the expensive operation of redistillation.

45 I claim:

1. In a fractionating tower for pressure stills and the like, an elongated shell, headers in the respective ends of said shell forming liquid chambers, circulating means receiving liquid from one of said headers and conveying it to the other, intermediate pairs of headers forming liquid chambers in said shell and dividing the same into vapor chambers, batteries of tubes extending through said vapor chambers and connecting the adjacent headers, ducts connecting adjacent vapor chambers, a vapor inlet to one of the end vapor chambers, a vapor outlet from the other end vapor chamber, and condensate draw-offs in each of said vapor chambers.

2. In a fractionating tower for pressure stills and the like, an elongated shell, headers in the respective ends of said shell forming

liquid chambers, circulating means receiving liquid from one of said headers and conveying it to the other, intermediate pairs of headers forming liquid chambers in said shell and dividing the same into vapor chambers, batteries of tubes extending through said vapor chambers and connecting the adjacent headers, ducts connecting adjacent vapor chambers, a vapor inlet to one of the end vapor chambers, a vapor outlet from the other end vapor chamber, condensate draw-offs in each of said vapor chambers and baffles in said vapor chambers to cause the vapors therein to pursue a circuitous path.

3. In a fractionating tower, a shell, end headers at the respective ends of the shell, forming end liquid chambers, intermediate headers forming liquid chambers and dividing the shell into a series of vapor chambers, batteries of tubes connecting adjacent headers and extending through the vapor chambers, by-pass ducts connecting the vapor chambers outside of said shell, a vapor inlet to one of the end vapor chambers, a vapor outlet from the other end vapor chamber, and condensate draw-offs from the respective vapor chambers.

4. In a fractionating tower the shell, end headers at the respective ends of the shell, forming end liquid chambers, intermediate headers forming liquid chambers and dividing the shell into a series of vapor chambers, batteries of tubes extending through the vapor chambers and connecting the headers at the ends thereof, connections between the vapor chambers, a vapor inlet to one of the end vapor chambers, a vapor outlet from the other end vapor chamber, condensate draw-offs from the respective vapor chambers, a heat interchanger for cooling the cooling liquid a connection from said heat interchanger to one of the end liquid chambers and, a pump connected to the heat interchanger and to the other end vapor chamber.

5. In a fractionating tower, a shell, end headers at the respective ends of the shell forming end liquid chambers, intermediate headers forming liquid chambers and dividing the shell into a series of vapor chambers, batteries of tubes connecting adjacent headers and extending through the vapor chambers, ducts connecting the vapor chambers, a vapor inlet to one of the end vapor chambers, a vapor outlet from the other end vapor chamber, condensate draw-offs from the respective vapor chambers, a by-pass pipe, connections from the intermediate liquid chambers to said by-pass pipe and valves in said pipe for controlling the passage of liquid therethrough.

JOHN E. BELL.
